UNITED STATES PATENT OFFICE.

WILLIAM B. MOORE, OF CHICAGO, ILLINOIS.

GAS GENERATOR.

1,402,785.

Specification of Letters Patent. Patented Jan. 10, 1922.

Application filed July 21, 1920. Serial No. 397,847.

To all whom it may concern:

Be it known that I, WILLIAM B. MOORE, a citizen of the United States, and a resident of Chicago, in the county of Cook and State of Illinois, have invented certain new and useful Improvements in a Gas Generator, of which the following, when taken in connection with the drawings accompanying and forming a part hereof, is a full and complete 10 description.

This invention relates to gas generators which are principally used to obtain gas suitable to maintain oxy-hydrogen flames.

Among the objects of this invention are 15 to obtain a gas generating apparatus which is durable, efficient in operation; which is readily understood and easily operated, and is economically operable.

In the drawings referred to—

20 Fig. 1 is a vertical sectional view of a gas generator embodying this invention, showing an oxy-hydrogen burner in elevation connected thereto, and

25 Figs. 2 and 3 are horizontal sections, on lines 2—2 and 3—3, of Fig. 1, respectively, viewed in the direction indicated by the arrows.

30 A reference character applied to designate a given part indicates said part throughout the several figures of the drawing, wherever the same appears.

35 A represents a vessel or container. B represents a chamber in said container, which is open at the top thereof, and adapted to hold water, and C an additional chamber, in said vessel, hereinafter termed the dehydrating chamber. Chamber C is separated from chamber B by horizontal partition b, said partition being termed a false bottom to said 40 chamber B. D represents a container having a lower and an upper chamber, (d, d¹), which are separated by the foraminated partition E; the smaller apertures in said partition being designated by the characters

45 e, e, and a large aperture in said partition by the character F. The aperture F is provided on the sides thereof with the upwardly extending lips or ribs f, f. G represents a pipe or tube which is open at one end and provided near the lower end thereof, (in chamber d¹) with the aperture g, communicating with said chamber. The lower end of this tube or pipe G is closed as by plug g¹. (See Fig. 1.) Said lower end is secured in partition E. H, H, (Fig. 2) represent abutments 50 to the walls of vessel A, adjacent to the upper

end of said walls. I represents a cross member which may be positioned on, or under said abutments H, H. When the apparatus is in operation, as will be hereinafter described, 60 said cross member I is positioned under abutments H, H, as is illustrated in Figs. 1 and 2. J represents a U-shaped member which is loosely mounted on cross member I, and K represents a screw threaded thumb 65 screw which fits in screw threaded aperture corresponding therewith in member J. Cross member I and the U-shaped member J are respectively provided with apertures which are slidably fitted on pipe or tube G, and 70 when thumb screw K is turned firmly against the side of cross member I, as is illustrated in Figs. 1 and 2 of the drawings, said members I and J are rigidly held thereby in any adjusted position on said pipe or 75 tube. Hence, by means of said members I, J, and K, the container D is adjustably placed and held in any desired position below the surface of the water, (represented by character X, in Fig. 1,) in chamber, B, 80 when the apparatus is in operation, as by gas generated in chamber d¹ said container D and pipe or tube G are forced upward, to bring the ends of cross member I against abutments H, H. L represents a flexible 85 tube which connects the upper end of pipe or tube G with the upper end of tube or pipe M. The lower end of said tube or pipe M is open and communicates with dehydrating chamber C. Pipe or tube M is 90 contained in chamber B, projecting a short distance into said dehydrating chamber, extending through the partition b, and being made water tight between it and said partition. N, O, O¹, respectively represent pipes 95 or tubes which communicate at the lower ends thereof with dehydrating chamber C. Pipe or tube N is contained in chamber B, and extends through the partition b, in a similar manner as does pipe or tube M, and 100 the upper end thereof communicates, (stop cock p being open) with the saturator S, through the flexible pipe P. The pipe or tube O is positioned outside of the vessel A, and the upper end thereof is in communication, (stop cock p¹ being open), with oxy-hydro burner Q, through flexible pipe p¹. The pipe or tube O¹ is also positioned outside the vessel A, and the upper end thereof is in communication with pipe or tube O. R represents a stick of lime, which is made incandescent by the flame directed thereunto from 105 110

nozzle q of burner Q . S represents a carbureter, known in the art as a saturator. It is loosely filled with cotton, and when about to be used is charged with liquid ether, and the flow of gas therethrough vaporizes said ether, the gas thereby becoming saturated therewith. By said vaporization the vaporized gas becomes cooled from the temperature at which the gas enters the saturator.

10 The discharge side of the saturator S is in communication with burner Q , (stop cock p^2 being open), by flexible pipe P^2 . r represents a base which is positioned to one side of the horizontal part Q^1 of burner Q , and is secured to and supported by member r^1 , mounted on said horizontal part. r^2 represents a flexible shaft, which extends through base r , being provided with screw threads fitting corresponding screw threads in said base, and with the hand wheel R^1 at one end thereof. Vertical adjustment of lime stick R relative to the nozzle q is obtained by turning the flexible shaft r^2 , by means of hand wheel R^1 . t represents a tube which is slidably mounted on horizontal part Q^1 of the burner, and is rigidly connected to member r^1 , (on one side of said base r), and to the member having thumb screw T therein. Lime stick R is adjusted horizontally 30 relative to nozzle q by sliding members r^1 and t on the horizontal part Q^1 of the burner and is secured in said adjusted position by the thumb screw T . U represents a base and u a standard to said base. u^1 represents a member which is slidable on standard u , and u^2 a thumb screw by means of which member u^1 is maintained in its adjusted position on said standard.

The burner Q with the several hereinbefore described members, elements and adjustments are known in the art, and for that reason a side elevation and a brief description thereof, sufficient to make known to those skilled in the art the method 40 of using an apparatus embodying this invention with an oxy-hydrogen burner, is all that is given herein.

The operation of the apparatus is; container D , pipe G , cross member I , member 50 J and thumb screw K , having been removed from chamber B and oxone inserted in chamber d^1 of said container, through aperture F , and said members replaced in chamber B , said chamber is nearly filled with water (X), and said water flows under the bottom edge of said container into chamber d and through the apertures in partition E , into chamber d^1 , there coming into contact with said oxone. Gas is generated and said 55 gas forces water, (by its expansion and pressure), out of said chambers d , d^1 , and thereby container D and its contents are of less specific gravity than said water, and said container forces pipe G and cross member I , (secured in an adjusted position

thereon as hereinbefore described), upward, and said cross member being turned, (together with container D and pipe G), to bring the ends of said cross member underneath abutments H , H , said container is 70 maintained in position below the surface of the water X , (determined by the adjustment of cross member I on pipe G). Gas generated as last above described flows into pipe G , through the open end of said pipe 75 from chamber d and through aperture g from chamber d^1 ; and from thence flows through pipe G , flexible pipe L and pipe M into the chamber G . In the generating of gas as last above described considerable 80 heat is developed and the water X is heated, the upper portion or part of said water becoming hotter than the lower portion or part thereof, and by conduction, the false bottom b is heated, but to a less degree 85 than the upper portion of water X . The contents of chamber C are thereby maintained in a warmed condition, but of less temperature than the upper portion of water X , and the extent of vapor saturation 90 of the contents of chamber C will be less than in pipes G , L , and M ; but greater than in pipes O and O^1 . Some of the contents of chamber C , determined by stop cocks p , p^2 , flow through pipes N , P , to 95 the saturator S , and from thence through pipe P^2 to burner Q , becoming saturated with vapor in its passage through the saturator S . The temperature of the gas flowing through pipe N to saturator S is increased from the temperature thereof in 100 chamber C by the increase in temperature in water X at the upper portion thereof, while the temperature of the gas flowing through pipe O is lowered, it not passing 105 through said water, but being outside thereof, and being further cooled in its flow through said pipe O , (or O^1). The desired difference in temperature in gas delivered to the saturator and directly to the burner is 110 thus secured.

Variation of pressure to the gas generated is obtained by the variation of the position of bar I on pipe G . Dehydration of the gas flowing through the pipe O , (or 115 O^1) is obtained by means of said gas cooling during said flow, and the water of condensation obtained flows back into chamber C ; hence the gas delivered from said pipe O to the burner is dry and comparatively cool. 120

While the water in chamber B is heated in the lower part thereof, (coming against the false bottom b), it is found in practice that the temperature of the water is the greatest at the top or surface thereof, the 125 heat gradually increasing from the bottom towards the top.

It is well known that evaporation of a liquid reduces the temperature of the container thereof; and in practice it is found 130

that by introducing heated gas to a saturator continuous evaporation can be effected therein without reducing the temperature of said saturator and of the contents thereof below an operable temperature, and by conducting gas from the dehydrating chamber C, upwards in pipe N, through the highly heated water in chamber B, and delivering said gas to the saturator as illustrated and described a hot gas, which is well dehydrated, is delivered to said saturator.

The delivery of a dry gas to the saturator and to the burner, one of said gases being cooled and the other at a high temperature, is thus effected; the said dryness of the cooled air being assured by the pipe or tube O¹, which in case any water from chamber C enters pipe or tube O, equalizes the pressure above said water with the pressure in said chamber, and thereupon said water in said pipe flows, by gravity, out of said pipe and into said chamber.

I claim;

- 25 1. A vessel provided with a water receptacle and a chamber, a plurality of pipes within said vessel and a plurality of pipes outside said vessel, all said pipes communicating with said chamber, in combination with a container removably positioned in said water receptacle, said container comprising a plurality of chambers with the partition common to said chambers horizontally disposed and foraminated, and a pipe 30 communicating with the upper one of said container chambers, and in communication with the upper end of one of said pipes within said vessel, and said pipes outside said vessel in communication with each other.
  - 35 2. A vessel provided with a water receptacle and a chamber, a plurality of pipes within said vessel and a plurality of pipes outside said vessel, all said pipes communicating with said chamber, in combination with a saturator, a burner, and a container,
  - 40
  - 45
- said container removably positioned within said water receptacle and comprising a plurality of chambers separated by a partition provided with apertures, and a pipe communicating with one of said container chambers, and with one of said pipes within the vessel and the other pipe within said vessel communicable with said saturator, and said pipes without said vessel in communication and one thereof, together with a pipe from 50 said saturator, communicable with said burner.
3. In a gas generator, a chamber, means, comprising a water containing vessel and an adjustable container in said vessel, to generate gas, means, to convey said gas to said chamber, and means to convey gas from said chamber to a burner, said last conveying means comprising communicating pipes positioned outside of said vessel and extending 55 into said chamber, one of said communicating pipes communicable with said burner, means, comprising a pipe positioned within said vessel, to convey gas from said chamber to a saturator, and means to convey gas from 60 said saturator to said burner.
4. In a gas generator, a chamber, means, comprising a water containing vessel and an adjustable container in said vessel, to generate gas, said adjusting means comprising 65 abutments adjacent to the upper end of said vessel, a cross member and a U-shaped member on said cross member, both thereof provided with an aperture, and a thumb screw arranged to be forced against said cross member, in combination with a pipe communicating 70 with said container and with said chamber, said pipe adapted to slide in said apertures, and means, comprising communicating pipes and an additional pipe to 75 convey gas from said chamber.
